DESIGN FOR A DUST PAN

Thomas Norman Badger, Berkeley, Calif.

Application September 12, 1932
Serial No. 44,816

Term of patent 14 years

To all whom it may concern:

Be it known that I, THOMAS NORMAN BADGER, a citizen of the United States, residing at Berkeley, in the county of Alameda and State of California, have invented a new, original, and ornamental Design for Dust Pan, of which the following is a specification, reference being had to the accompanying drawing, forming part thereof.

Figure 1 is a top plan view of the dust pan, showing my new design;

Figure 2 is a cross-sectional view taken along line 2—2 of Fig. 1, the handle being shown broken off;

Figure 3 is a perspective view, on an enlarged scale, the handle being shown broken away for convenience of illustration.

I claim:

The ornamental design for a dust pan, as shown and described.

THOMAS NORMAN BADGER.
